WILLARD H. SMITH, OF NEW YORK, N. Y., ASSIGNOR TO FRANCIS C. CANTINE, OF ORANGE, NEW JERSEY.

Letters Patent No. 86,118, dated January 19, 1869; antedated January 6, 1869.

IMPROVEMENT IN LAMPS.

The Schedule referred to in these Letters Patent and making part of the same

To all whom it may concern:

Be it known that I, WILLARD H. SMITH, of the city, county, and State of New York, have invented a new and useful Improvement in Insulating Buttons of Argand-Burners; and I do hereby declare the following to be a full and correct description of the same, sufficient to enable others skilled in the art to which my invention appertains, to fully understand and make the same, reference being had to the accompanying drawings, which make part of this specification, and in which—

Figure 1 is a side elevation of the improved burner; Figure 2 is a top view of the same;

Figure 3 is a central vertical section of the same; and Figure 4 is a detached view of a part of the same.

Like letters of reference indicate like parts in the several figures.

The nature of my invention consists in so insulating the button and button-rod of an argand-burner that the heat of the same cannot be communicated to the burner itself.

In the drawing—

A may represent an argand-burner, in which the rack-bar or button-rod, B, which bears the button C, is held, in suitable bearings, by means of the guides D.

The bearings, in which the rod B moves vertically, consist of an inner ring, a, and an outer one, B, between which a packing, c, is placed, which consists of

a ring, of cork, or any other suitable non-conductor of heat.

E represents the toothed wheel on the elevator-rod F, by means of which the rack-bar B and button C are elevated. Heat might be communicated through this wheel from the rack-bar to the burner. To prevent this, I construct the bearing on the burner, through which this elevator-rod passes, in the same manner as the bearings of the rack-bar B.

It is well known that, in burners of this kind, the button heats quickly, and intensely, which heat, being communicated through the burner to the oil, causes the same to fill the burner, and, when the lamp is extinguished, a bad smell to pervade the room, caused by the oil on the surface of the burner.

By my improvement the heat is not communicated to the oil, and thus the bad odor, on extinguishing a lamp, prevented.

Having thus described my invention,

What I claim as new therein, and desire to secure by Letters Patent, is—

Insulating the button and button-rod of argand-burners, in the manner substantially as herein described.

W. H. SMITH.
